(57) **CLAIM**

The ornamental design for an apparatus for measuring refractive power of lens, as shown and described.

DESCRIPTION

FIG. 1 is a perspective view taken from the front, upper and left side of the apparatus for measuring refractive power of lens;

FIG. 2 is a perspective view taken from the front, upper and right side of the apparatus for measuring refractive power of lens;

FIG. 3 is a front view of the apparatus for measuring refractive power of lens;

FIG. 4 is a rear view of the apparatus for measuring refractive power of lens;

FIG. 5 is a left side view of the apparatus for measuring refractive power of lens;

FIG. 6 is a right side of the apparatus for measuring refractive power of lens;

FIG. 7 is a plan view of the apparatus for measuring refractive power of lens; and,

FIG. 8 is a bottom view of the apparatus for measuring refractive power of lens.
